CLAIM

The ornamental design for a movement auxiliary tool, as shown and described.

DESCRIPTION

FIG. 1 is a front view of a movement auxiliary tool showing our new design;
FIG. 2 is a rear view thereof;
FIG. 3 is a right lateral view thereof;
FIG. 4 is a left lateral view thereof;
FIG. 5 is a perspective thereof;
FIG. 6 is a top view thereof; and,
FIG. 7 is a bottom view thereof.

(Continued)

The broken lines shown in FIGS. 1-7 illustrate portions of the movement auxiliary tool and form no part of the claimed design.
